CLAIM

The ornamental design for a charger base for a hand-held vacuum cleaner or similar appliance, as shown and described.

DESCRIPTION

FIG. 1 is a front and upper left perspective view of a charger base for a hand-held vacuum cleaner or similar appliance showing our new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof;

FIG. 7 is a rear elevational view thereof; and,

FIG. 8 is a rear and upper right perspective view thereof.

The broken line showing of a tool which can be mounted on the base in FIGS. 2, 3, 4 and 5 is included for the purpose of illustrating environmental elements and forms no part of the claimed design.
